(57) **CLAIM**

The ornamental design for an eyeglasses case, as shown and described.

DESCRIPTION

FIG. 1 is a perspective view of an eyeglasses case in a closed configuration.

FIG. 2 is a back view of the eyeglasses case of FIG. 1 in the closed configuration.

FIG. 3 is a front view of the eyeglasses case of FIG. 1 in the closed configuration.

FIG. 4 is a left-side view of the eyeglasses case of FIG. 1 in the closed configuration.

FIG. 5 is a right-side view of the eyeglasses case of FIG. 1 in the closed configuration.

FIG. 6 is a top view of the eyeglasses case of FIG. 1 in the closed configuration.

FIG. 7 is a bottom view of the eyeglasses case of FIG. 1 in the closed configuration.

FIG. 8 is a perspective view of an eyeglasses case of FIG. 1 in an open configuration.

FIG. 9 is a back view of the eyeglasses case of FIG. 1 in the open configuration.

FIG. 10 is a front view of the eyeglasses case of FIG. 1 in the open configuration.

FIG. 11 is a left-side view of the eyeglasses case of FIG. 1 in the open configuration.

FIG. 12 is a right-side view of the eyeglasses case of FIG. 1 in the open configuration.

FIG. 13 is a bottom view of the eyeglasses case of FIG. 1 in the open configuration; and,

FIG. 14 is a top view of the eyeglasses case of FIG. 1 in the open configuration.

1 Claim, 14 Drawing Sheets
